UNITED STATES PATENT OFFICE.

JAMES H. GRAY, OF NEW YORK, N. Y.

REGENERATOR CHAMBER.

1,408,086.

Specification of Letters Patent. Patented Feb. 28, 1922.

Application filed June 15, 1921. Serial No. 477,766.

To all whom it may concern:

Be it known that I, JAMES H. GRAY, a citizen of the United States, residing in the city, county, and State of New York, have invented certain new and useful Improvements in Regenerator Chambers, of which the following is a specification.

My invention aims to provide certain improvements in regenerator chambers for metallurgical furnaces and particularly for open hearth steel furnaces.

The accompanying drawings illustrate an embodiment of the invention.

Fig. 1 is a horizontal section of a regenerator chamber with a dust catcher and passages leading from the furnace;

Figs. 2 and 3 are vertical sections on the line 2—2 and 3—3 of Fig. 1 respectively.

Referring to the embodiment of the invention illustrated, an upright flue 1 communicates at its upper end with the furnace for conveying thereto air which has been preheated in the regenerator, or for conveying the gases of combustion from the furnace to the regenerator.

At the lower end of the flue 1 is a slag pocket 2 having at its end a bridge wall 3 over the top of which the gases pass (usually directly to the regenerator). In the present case the gases pass over the bridge wall through a port 4 to a channel which passes around the outside of the regenerator, this channel comprising an oblique side 5 and longitudinal and transverse passages 6, 7 and 8 respectively, the latter communicating at its upper portion with a port 9 over a bridge wall 10 leading directly to the regenerator. The regenerator proper is enclosed within a wall composed of parts 11, 12, 13 and 14 having rounded corners, while outside of the adjacent passages the walls 15, 16, 17 and 18 are preferably arranged with angular internal corners. From the port 9, the gases pass over the top of the checker work 19 and thence down through the same to heat it in the usual manner and out through the grating or perforated floor 20 thereof, and thence by suitable passages, not illustrated, to a main flue communicating alternately with the stack or with the incoming air.

The gases coming from the furnace deposit the comparatively large pieces of slag carried therein in the pocket 2. The remaining gas passing through the port 4 is drawn through the passages 5, 6, 7 and 8

with a centrifugal effect which is particularly emphasized at the corners where there is an abrupt change in direction so that the dust from the gases is deposited largely in these corners, whence it can be drawn out through suitable openings on a level with the floor of these passages. The air enters the dust separating passage at the top and leaves it at the top so that there is little or no tendency to carry along with it the dust which has once been separated and fallen to the floor.

It was formerly almost universal practice to use for fuel in open hearth furnaces and other regenerative heating furnaces, a gas derived from coal, gasified in gas producers. To obtain intense combustion and high temperature, it was necessary to heat the gas as well as the air in regenerative chambers before burning. For this purpose, two regenerative chambers were provided at both ends of the furnace, one chamber to heat the air and the other to heat the gas. These chambers usually lay parallel to each other, being separated by a wall or walls, the air chamber being of about twice the cubical content of the gas chamber.

At the present time, fuels are being used in regenerative furnaces which do not need to be heated in regenerative chambers, for instance, by-product coke oven gas, oil, tar, pulverized coal, etc. Consequently, there are in existence a large number of furnaces provided with double chambers and giving an excess heating area as regards the air alone. In such furnaces, I throw the two chambers together by removing the separating wall or walls, and thus I utilize space equivalent to the gas chamber for the passages 5, 6, 7 and 8, and retain the same amount of checker brick as before, for heating the air. In most installations of furnaces, the floor space available for the putting down of regenerative chambers is limited.

My improvement, therefore, is particularly adapted for furnaces using fuel which does not require preheating, and provides a combined regenerator and separator within a space no greater than that which has heretofore been used for gas and air regenerators in the old style furnaces. The hot air passing around the regenerator also transmits heat thereto through the interior walls of the dust separating passages.

Though I have described with great par-

ticularity of detail a specific embodiment of my invention, yet it is not to be understood therefrom that the invention is restricted to the particular embodiment disclosed. Various modifications thereof in detail and in the arrangement of the parts may be made by those skilled in the art without departure from the invention as defined in the following claims.

10 What I claim is:

1. A regenerator for metallurgical furnaces having a surrounding passage for the gas coming from the furnace to the regenerator in which dust is separated by centrifugal action.

2. A regenerator for metallurgical furnaces having a surrounding passage for the gas coming from the furnace to the regenerator in which dust is separated by centrifugal action, said passage having angular corners to make an abrupt change of direction of the gas.

3. A regenerator for metallurgical furnaces having a surrounding passage for the gas coming from the furnace to the regenerator.

ator in which dust is separated by centrifugal action, said passage having an admission port and a discharge port for the gases, both of which are above the floor of the passage.

4. A regenerative metallurgical furnace adapted to preheat the air but not the fuel for combustion and having an air regenerator and a dust separating passage surrounding said regenerator.

5. A regenerative metallurgical furnace adapted to preheat the air but not the fuel for combustion and having an air regenerator and a dust separating passage along the two sides and around the outer end wall of said regenerator.

6. A regenerative metallurgical furnace adapted to preheat the air but not the fuel for combustion and having an air regenerator with vertical passages therethrough and a dust separating passage extending along a side wall of said regenerator.

In witness whereof, I have hereunto signed my name.

JAMES H. GRAY.
